LOCK-UP KEY FOR CHASE

Leon R. Hedges, Wichita, Kans.

Application April 2, 1958, Serial No. 726,016

4 Claims. (Cl. 81—177)

This invention relates to printing and the printing industry. In a more specific aspect this invention relates to means which are conveniently employed in printing processes. In still a more specific aspect this invention relates to a lock-up or quoin key or wrench which is most desirably used to turn lock-up screws or bolts which work with the quoins in a printing chase to hold and secure therein composed type, illustrations, etc.

Printing is one of our older arts, and the printing industry is one of our largest. It is common in the printing industry in carrying on the processes of printing to employ what is known as a chase. A chase is a frame structure, usually rectangular, in which composed type, illustrations, etc., are secured or locked, for use in the printing operations or for use in making printing plates. Quoins are used in conjunction with and co-operate with a chase to hold composed type, etc., secured or locked therein. These quoins are usually made of wood or metal and are of various shapes, such as wedge-shaped, square or rectangular blocks, odd interacting shapes, etc. In use they fit between the chase which is usually wood or metal and the composed type, etc., or between sections of the composed type. Lock-up screws or bolts are normally threadedly engaged in and pass through one or more sides of the chase, these bolts or screws acting in a setscrew manner to exert force on the quoins and composed type to hold them locked together and secured within the chase. In printing operations it is the usual practice to use any of a number of common wrenches or pliers to turn these lock-up screws or bolts for the securing of the composed type or for releasing of the quoins and composed type so that they may be removed from the chase. It has been my experience that plier and common wrench turning means become lost or misplaced, since they cannot conveniently be carried in the pocket of the usual apron which a printer uses while working. A great deal of time and effort is thus lost, making for great inefficiency of operation. I have invented a new quoin key or wrench which when not in use can be folded up or closed so that it can conveniently be carried in the pocket of a printer's apron, safely and conveniently. The new quoin key or wrench of my invention can be made light and small so that no interference with the printer occurs when carrying the quoin key or wrench.

The new quoin key or wrench of my invention has a handle, and a head member. The head member has means therewith which are constructed to engage a lock-up screw or bolt of a chase in turning relation. The head member is movably mounted on the handle so that the head member can be positioned in either of two positions. These two positions are in open operating position for turning a lock-up screw or bolt of a chase, and a closed position for carrying the quoin key or wrench. Retractable catch means are constructed into and mounted relative to the handle and head member of the quoin key or wrench. In extended position, these catch means maintain the key or wrench in the open operating position, and in retracted position these catch

2

means permit the wrench or key to be placed in closed position for carrying, such as in the pocket of a printer's apron.

It is an object of this invention to provide new means for the printing industry.

It is another object of this invention to provide new key or wrench means for turning screws or bolts.

A further object of this invention is to provide new quoin key or wrench means for turning lock-up screws or bolts in a printing chase.

Still another object of this invention is to provide new, conveniently usable quoin-key or wrench means for turning lock-up screws or bolts in a printing chase, such key or wrench means being adapted to be folded or placed in closed position for safe and easy carrying by the printer, and such key or wrench means being simple and easy to make and use.

Other objects and advantages of the new quoin key or wrench means of my invention will become apparent to those skilled in the art upon reading this disclosure.

Drawings accompany and are apart of this disclosure. These drawings depict preferred specific embodiments of the new quoin key or wrench means of my invention, and it is to be understood that they are not to unduly limit the scope of my invention.

In the drawings,

Fig. 1 is a side elevation of a preferred specific embodiment of the new quoin key or wrench of my invention.

30 Fig. 2 is an enlarged vertical section taken on line 2—2 of Fig. 1.

Fig. 3 is an enlarged vertical section taken on line 3—3 of Fig. 1.

Fig. 4 is a partial view in plan of a chase with quoins and composed type therein and having lock-up screws or bolts which are preferably turned by the new quoin key or wrench of my invention.

Following are a discussion and description of the new quoin key or wrench of my invention made with reference to the drawings whereon the same reference numerals are used to indicate the same or similar parts or structure. The discussion and description are of preferred specific embodiments of the new quoin key or wrench of my invention, and it is to be understood that such discussion and description are not to unduly limit the scope of my invention.

Referring now to the drawings, the quoin key or wrench 6 has a handle 8, which is preferably elongated and round in cross section in the rearward end portion 10 and with 50 straight sides, preferably square in cross section, in the forward end portion 12. The forward end portion 12 preferably has a hollow 14 formed therein, and a slot 16 in the top side communicating between the outside of the handle and the hollow 14. Of course, an aperture of any shape or size can be used which is suitable. It is preferred that the opposite sides of the hollow 14 (Fig. 2) be inclined inwardly in their upper portions adjacent the slot 16 so as to form the inwardly projecting ledge portions of the handle portion 12 relative to the hollow 14. As will be set forth hereinafter, this is a desirable means to limit the travel of the catch discussed herein-after, and to prevent such catch from escaping from the hollow 14.

65 The wrench or quoin key 6 has a head 18. This head is preferably flat and rectangular as shown in the drawings. It has an aperture 20 in the outer end portion, preferably a square hole 20 as shown in the drawings to receive a portion of the usual beveled lock-up screw or bolt 22 of the usual printing chase 24. In operation the key head 18 engages the lock-up screw or bolt head 22 in turning relation. Bracket means are suitably attached to the other end portion of key or wrench head 18. These

bracket means are preferably a pair of oppositely spaced brackets 26 which project inwardly from the wrench head 18. These brackets 26 are used to pivotally mount the key or wrench head 18 on the forward end portion 12 of handle 8. Pins 28 suitably secured to brackets 26 and projecting into recesses formed in the sides of end portion 12 of handle 8 have been found convenient and desirable to pivotally mount the wrench head 18. The brackets 26 overlap the end portion 12 of handle 8 and are preferably snugly adjacent the straight sides of end portion 12, so that when in the position shown by the solid lines of Figs. 1 and 2, the wrench head 18 is in turning relation to the handle 8, that is, so that when the wrench or key 6 is moved in cranking action relative to the lock-up screw or bolt 22 through the handle 8 the screw or bolt 22 will be turned.

A retractable catch 30 is preferably employed and mounted in the hollow 14 and slot 16 of end portion 12 of handle 8.

The catch 30 preferably has an enlarged inner portion 32 with beveled upper sides as shown in Fig. 2 of the drawings. The bevel corresponds to the bevel of the upper portion of the sides of hollow 14, and the portion 32 of catch 30 engages the inwardly extending handle portions, when the catch 30 is extended, to prevent escape of the catch 30 from the hollow 14. The catch 30 has a central portion which extends through the slot 16, and an outer projecting portion 34 which is constructed to engage the wrench head 18 when the catch 30 is extended and the wrench is in open position, the position shown in solid lines in Figs. 1 and 2. This provides for maintaining the wrench in open position against pressures thereon which would tend to close or fold wrench head 18. The catch 30 is retractable, preferably by finger pressure, so that the key or wrench can be closed or folded for carrying, this closed or folded position of the wrench head 18 being shown in Fig. 1 in dotted lines. Resilient means are mounted in the hollow 14 to urge the catch 30 into extended position. These resilient means are preferably a helical spring 36 which is in compression and which engages the bottom of catch 30 and the bottom of hollow 14. It is preferred to design the wrench so that the catch 30 will press against the wrench head 18 when in closed or folded position to maintain such in this position. Then the wrench, under slight pressure, can be moved into open position. The design shown in the drawings accomplishes this, because when in folded position the force of catch 30 is perpendicular to the wrench head 18 and does not exert any turning force thereon.

The outer end portion of the end portion 10 of handle 8 can conveniently be made hollow as shown in the drawings. This hollow 38 is desirably used to hold a pica-calibrated tape 40 of the spring-loaded kind, which can be extended by pulling on an outer end 42, and which automatically rewinds itself around pin mounting means 44 suitably secured in the walls of handle 8. In extending the tape 40, it passes out through a slot 46 in the end 48 of the handle 8.

The quoin key or wrench 6 of my invention is used to loosen or tighten lock-up screws or bolts 22 which are threadedly engaged in the sides of chase 24 (Fig. 4). In printing and printing operations the chase 24 holds quoins such as elongated quoins 50, and interacting quoins 52 and 54. These quoins 50, 52, and 54 act to hold diagrammatically depicted composed type, etc., 56 and lock and secure the type 56 in the chase 24. In operation the new quoin key or wrench of my invention is mounted for use on the lock-up screw or bolts 22 in the manner depicted in Figs. 1 and 2 of the drawings.

As will be evident to those skilled in the art, various modifications of this invention can be made, or followed, in the light of this disclosure and discussion, without departing from the spirit or scope of the disclosure or from the scope of the claims.

I claim:

1. A quoin key or wrench comprising, in combination, an elongated handle round in cross section in the rearward end portion and square in cross section in the forward end portion, said forward end portion having a hollow and a slot in one side communicating between the outside thereof and said hollow, opposite sides defining said hollow being inclined inwardly adjacent said slot to form inwardly projecting ledge portions of said handle relative to said hollow, a flat, rectangular, wrench head having a square hole in one end portion of size to receive a portion of the head of a beveled chase lock-up screw or bolt in turning relation and attached thereto in the other end portion a pair of oppositely spaced brackets projecting therefrom, said wrench head being pivotally mounted on said forward end portion of said handle by pin means secured to said brackets and with said brackets overlapping opposite sides of said handle and so that in open operating position said wrench head is at right angles to said handle and turnably locked relative to said handle and in closed carrying position said wrench head lies flat against said handle longitudinal thereto, a retractable catch mounted in said hollow of said handle, said catch having an enlarged inner portion with beveled upper sides engaging said handle when said catch is extended, a central portion projecting through said slot and an outer portion constructed to engage said wrench head when said catch is extended and said wrench is open to maintain said wrench in open position, said catch being retractable to permit folding said wrench head, and a helical spring mounted in said hollow of said handle, engaging said catch and urging said catch into extended position.

2. A quoin key or wrench comprising, in combination, a handle having opposite straight sides in the forward end portion, said forward end portion having a hollow and a slot in a side between said straight sides, said slot communicating between the outside of said handle and said hollow, a portion of said handle defining said slot projecting inwardly beyond a side of said hollow within said handle, a wrench head having an aperture in one end portion of size and shape to receive a chase lock-up screw in turning relation and in the other end portion bracket means projecting therefrom, said wrench head being pivotally mounted on said forward end portion of said handle with said bracket means overlapping said handle and the brackets thereof being adjacent to said straight sides of said forward end portion of said handle, said wrench head when pivoted into open position having its longitudinal axis transverse the longitudinal axis of said handle and being in turnable relation with said handle and in retracted position said wrench head having its longitudinal axis substantially parallel to the longitudinal axis of said handle and with said wrench head lying substantially flat against said handle, a retractable catch mounted in said hollow of said handle, said catch having an inner portion constructed to engage a portion of said handle to prevent said catch from exiting from said hollow of said handle when in extended position, a central portion projecting through said slot and an outer portion constructed to engage said wrench head when extended to maintain said wrench head in open position, said catch being retractable to permit closing said wrench head, and resilient means mounted in said hollow of said handle and urging said catch into extended position.

3. A quoin key or wrench comprising, in combination, a handle, a wrench head having an aperture in one end portion to receive a chase lock-up screw in turning relation and in the other end portion being pivotally mounted on one end portion of said handle in a manner such that said wrench head when in open position has its axis transverse the axis of said handle and when in retracted position has its axis substantially parallel said axis of said handle, retractable catch means in said end portion of said handle constructed and mounted so that

when extended said catch means maintains said wrench head in open position and in turnable relation with said handle and so that when retracted said wrench head can be folded, and means urging said catch means into extended position.

4. A quoin key or wrench comprising, in combination, a handle, a wrench head member having means to receive a chase lock-up screw in turning relation, said wrench head member being pivotally mounted on said handle in a manner such that said wrench head member when in open position has its axis transverse the axis of said handle and when in retracted position has its axis substantially parallel said axis of said handle, retractable

5 catch means with said handle constructed and mounted so that when extended said catch means maintains said wrench head in open position and in turnable relation with said handle and so that when retracted said wrench head can be folded, and means urging said catch means into extended position.
